(57) **CLAIM**

The ornamental design for an oral care implement, as shown and described.

DESCRIPTION

FIG. 1 is a front right perspective view of an oral care implement;

FIG. 2 is a rear left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the figures that are immediately adjacent to the shaded areas and define unshaded regions are used solely for the purpose of illustrating environmental boundaries. All other broken lines, including the features within broken line boundaries, are directed to environment. The broken lines form no part of the claimed design.
